Primary Examiner — Karen E Eldridge Powers*(74) Attorney, Agent, or Firm* — Vladimir Vitenberg(57) **CLAIM**

The ornamental design for a head for electric toothbrush, as shown and described.

DESCRIPTION

FIG. 1 is a perspective view of a head for electric toothbrush; FIG. 2 is a front elevation view thereof;

FIG. 3 is a right-side elevation view thereof;

FIG. 4 is a rear elevation view thereof;

FIG. 5 is a left-side elevation view thereof;

FIG. 6 is a top plan view thereof; and,

FIG. 7 is a bottom view thereof.

Broken lines are used in the drawings to designate environmental structures or parts of the head for electric toothbrush that form no part of the claim.
